UNITED STATES PATENT OFFICE.

PETER F. SCHNEIDER, OF DETROIT, MICHIGAN.

PISTON AND VALVE-OPERATING MECHANISM FOR WATER-MOTORS.

1,369,134.

Specification of Letters Patent. Patented Feb. 22, 1921.

Application filed May 20, 1918. Serial No. 235,532.

To all whom it may concern:

Be it known that I, PETER F. SCHNEIDER, a citizen of the United States, residing at Detroit, county of Wayne, State of Michigan, have invented a certain new and useful Improvement in Piston and Valve-Operating Mechanism for Water-Motors, and declare the following to be a full, clear, and exact description of the same, such as will enable others skilled in the art to which it pertains to make and use the same, reference being had to the accompanying drawings, which form a part of this specification.

This invention relates to pistons and valve operating mechanism for water motors, and its object is to provide a piston and valve operating mechanism that is simple in construction and efficient in operation and in which the construction is of a character to allow the use of a comparatively long coiled spring to secure the required movement of the valve operating part, and further to provide a valve operating mechanism in which the extent of compression of the spring may be adjustably limited thus avoiding compression of the spring to such extent that breakage may occur and to vary the initial tension thereof. These several objects and the novel features of the invention are hereinafter more fully described and claimed and shown in the accompanying drawings in which—

Figure 1 is an elevation partly in section of the water motor showing my improved valve operating mechanism and piston.

Fig. 2 is a longitudinal section of a piston and valve operating mechanism carried thereby.

Fig. 3 is a detail of the device for adjusting the spring tension.

Fig. 4 is a vertical section of the valve mechanism.

In water motors of the character here shown two cylinders 1 and 2 are provided on opposite sides of a central portion 3 having chambers into which leads an intake 5 and an outlet 4 respectively for the water. Each cylinder is closed at the bottom as is shown with the cylinder 2 by means of the wall 6 of the portion 3 which wall is apertured to receive the intake and discharge valves 7 and 8. These valves are connected on the interior of each cylinder by means of a plate or bar 9 connected with the stems 55 of the valves. The valves are seated in the position of parts shown in Fig. 1 and by

pressing centrally on the plate 9 behind the valves, the ports 8 and 7 are opened allowing water to flow into the cylinder through the port 7 to force the piston outward in the cylinder and on reverse movement discharge water through the port controlled by the valve 8. The pistons 10 of the two cylinders are similar in construction and are connected together by a bar 11 which is attached to the ends of each piston rod 12 by means of a bolt 13 extending into the rod. The motor here shown is a type used with washing machines and the mechanism to be operated by the piston is connected to this bar 11 (not here shown).

The motor described is in all respects similar to motors now commonly in use for this purpose. Pistons have also been provided with a projecting stem of the character shown at 14 although differing in this respect in that the stem is short and held in position by a very short spring capable of but little compression. Such springs frequently break in the operation of the motor and prevent efficient operation thereof in that the valves will only open by spring pressure when the water has less pressure. This invention seeks to provide a long spring that is flexible in character having considerable range of tension and yet limited as to the extent of compression in order that the spring may not be unduly compressed in a manner to cause breakage and further operating the valves under various pressure of water. To accomplish this the piston rod is made hollow as shown in Fig. 2 and at the end thereof is provided a flexible piston member 15 engaging the cylinder wall and inclined toward the valve end of the cylinder. Water being admitted into the cylinder tends to expand the flexible portion 15 of the piston and prevent leakage of water between the piston and cylinder. This piston member 15 is held in position by a nut 16 which has a central aperture through which the stem 14 projects.

In my invention this stem is provided with a cylindrical portion 17 riding in the interior of the rod 12 of the piston and being preferably provided with two portions 19 and 20 slightly greater in diameter than the body contacting the walls of the rod and being of comparatively small surface the friction is reduced to a minimum. The portion 19, for instance, provides a shoulder against which the coiled spring 21 engages

which is a comparatively long coil and this coil is held in position in engagement with the shoulder by means of the bolt 13 threaded in the outer end 12 of the piston rod as shown. The bar 11 has a terminal aperture through which the bolt engages and the bar is held between the bolt head and end of the rod so that movement of the piston 10 reciprocates the bar 11 as will be readily understood. On inward movement of the piston in the cylinder 2 for instance, caused by outward movement of the piston in the cylinder 1 the valve operating stem 14 (as the piston 10 in the cylinder 2 approaches the bottom of the cylinder) engages the valve plate 9 opening the normally closed inlet valve for the cylinder 2 and closing the said valve for the cylinder 1. During the intake stroke of the piston 10 the water in the cylinder passes outward through the outlet valve 8 and these valves 7 and 8 control the intake and outlet ports of both cylinders when closed to one, being open to the other which construction is well known.

It is to be noted that on the inward stroke of the piston 10 the stem 14 engages the plate 9 loosely connecting the valves together and that the inlet valve 7 is opened when the tension of the spring controlling the stem 14 becomes greater than the pressure of the water holding the valve closed. It is this function that is obtained in the construction here shown with the long coiled spring that is impossible of achievement by the older types having short springs. As there is considerable variation possible in the tension of the spring prior to attaining the limit of compression, the water motor may be placed in one part of the city in which the pressure is high and operate efficiently and may be moved from there to other portions of the city where the pressure is much lower and still operate fully as efficiently without necessity of adjusting the parts.

I prefer to limit the movement of the stem by means of a rod 22 provided centrally within the coiled spring 21. This rod is somewhat less in length than the length of the spring but is preferably of such length that, prior to the spring being compressed with the coils in contact one with the other, the outer end of the rod will be engaged by the end of the bolt 13 threaded in the stem 12 of the valve and thus prevent an undue compression of the spring. In order that the initial tension of the spring may be varied I have provided the bolt with an adjustable end member 23 cylindrical in form and slideable within the hollow stem 12. This member 23 is provided with a stem 24 in threaded relation with a central aperture extending longitudinally of the bolt 13. This stem may be provided with a screw head 25 at the outer end of the bolt by means

of which the position of the member 23 may be varied relative to the bolt and thus vary the initial tension of the spring. The rod 22 heretofore mentioned is preferably separate from the part 17 for the purpose of cheapness but may be made integral with the part 17 if so desired. By this described arrangement a comparatively long coiled spring may be utilized flexibly supporting the stem and allowing a considerable range of movement of the stem 14 whereby the device is applicable for use under varying water pressures, and further by providing the adjustable member 23 various initial tensions of the spring 21 may be produced whereby the initial pressure at which the spring will operate the valves may be varied and liability of breakage is reduced to a minimum by reason of the limiting bar or rod 22.

Having thus briefly described my invention, what I claim and desire to secure by Letters Patent of the United States is—

1. A piston and valve operating mechanism for water motors comprising in combination with a piston, a hollow stem therefor, a plunger reciprocable within the stem and extending through the piston, a coiled spring in the stem normally maintaining the plunger in position, and a bolt in threaded relation with the piston stem and seating against the end of the spring.

2. A piston and valve operating mechanism comprising in combination with a piston, a hollow stem therefor, a plunger reciprocable within the stem and having a portion extending through the piston, a coiled spring holding the plunger in position, a bolt in threaded engagement with the piston rod or stem and seating against the spring, and a rod or bar less in length than and positioned within the coiled spring limiting the extent of compression of the spring.

3. A piston and valve operating mechanism for water motors comprising in combination with the piston, a hollow stem or rod, the piston being secured to the rod, a nut thereon for holding the piston in position and closing the end of the stem, the nut having a central aperture, a plunger in the rod having a stem projecting through the aperture, said plunger having a shoulder, a coiled spring seating thereagainst, a bolt or the like threaded in the piston rod and holding the spring in engagement with the said seat, and means limiting the extent of movement of the plunger in the rod.

4. The combination in a water motor having two oppositely disposed cylinders and pistons and a valve chamber therebetween having inlet and exhaust ports for each cylinder and valves reciprocable in the chamber to close first one set of ports and then the other, of a valve operating mech-

anism comprising a hollow stem for each piston, a plunger reciprocable within the stem and extending through the inner face of the piston, a coiled spring in the stem 5 normally maintaining the plunger in projected position, means in the stem engaging the end of the spring, said means being adjustable longitudinally of the stem to vary the tension of the spring.

10 5. The combination in a water motor having two oppositely disposed cylinders and pistons and a valve chamber therebetween having inlet and exhaust ports for each cylinder and valves reciprocable in the chamber to close first one set of ports and then 15 the other, of a valve operating mechanism

comprising a hollow stem for each piston, a plunger in each stem reciprocable therein and having a portion extending through the face of the piston, a coiled spring in the stem 20 normally maintaining the plunger in projected position, means for adjusting the tension of the spring, means limiting the extent of compression of the spring, and a bar in each cylinder connecting the stems of 25 the said valves, said bar being adapted to be engaged by the projecting stem to reciprocate the valves.

In testimony whereof I sign this specification.

PETER F. SCHNEIDER.
